Primary Examiner — T Chase Nelson*Assistant Examiner* — Jeff Lenard D Torres(74) *Attorney, Agent, or Firm* — Marshall A. Lerner; Steven J. Kim; KLEINBERG & LERNER, LLP(57) **CLAIM**

The ornamental design for a shoe midsole periphery, as shown and described.

DESCRIPTION

FIG. 1 is a front perspective view of a shoe midsole periphery in accordance with my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

Broken lines shown in the drawing represent environmental structure of the shoe and portions of the shoe midsole periphery that form no part of the claimed design.

1 Claim, 8 Drawing Sheets(56)
